CLAIM

The ornamental design for an angled grip, as shown and described.

DESCRIPTION

FIG. 1 is a front perspective view of an angled grip; FIG. 2 is front elevation view thereof; FIG. 3 is a rear elevation view thereof; FIG. 4 is a right-side view thereof; FIG. 5 is a left-side view thereof; FIG. 6 is a top view thereof; FIG. 7 is a bottom view thereof; FIG. 8 is a rear perspective view thereof; and, FIG. 9 is a side view thereof with a firearm shown in broken lines to illustrate environmental structure. The broken lines in the drawings showing portions of the angled grip as well as those showing a firearm in FIG. 9 form no part of the claimed design.

1 Claim, 9 Drawing Sheets(56)
